FOREIGN PATENT DOCUMENTS

JP D1199147 S 3/2004

* cited by examiner

Primary Examiner — Mark Goodwin(74) *Attorney, Agent, or Firm* — Antonelli, Terry, Stout & Kraus, LLP.(57) **CLAIM**

We claim the ornamental design for a swing post for a construction machine, as shown.

DESCRIPTION

FIG. 1 is a front, top and left side perspective view of a swing post for a construction machine showing our new design;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof; and,
 FIG. 7 is a bottom plan view thereof.
